Int. Cl. D6—04

U.S. Cl. D6—164

FIG. 1

FIG. 2

FIG. 3

FIG. 4

FIG. 5

FIG. 1 is a perspective view from the front and left of and slightly above my kitchen counter dual access cabinet;

FIG. 2 is a rear elevation view of the kitchen counter dual access cabinet illustrating the dual access drawer;

FIG. 3 is a view in rear elevation of the cabinet of FIG. 1 but wherein the lower portion thereof is provided with paired door members rather than a plain unornamented surface as in FIG. 2;

FIG. 4 is a perspective view showing the front and top of my kitchen counter dual access cabinet with the front access doors to the lower section of the cabinet open showing a compartmentalized spool assembly for the storage of kitchen ware such as pots and pans; and

FIG. 5 is a perspective view showing the front and top of my kitchen counter dual access cabinet with the dual access drawer withdrawn to show a compartmentalized

turntable for the storage of kitchen flatware and miscellaneous utensils.

I claim:

The ornamental design of the kitchen counter dual access cabinet, substantially as shown and described.
